United States Patent

Des. 240,965
Patented Aug. 10, 1976

240,965

COIN OPERATED REPRODUCTION MACHINE

Claude H. Hutcheson, Jr., Fairport, and Larry H. Warren,
East Rochester, N.Y., assignors to Xerox Corporation,
Stamford, Conn.

Filed Mar. 28, 1974, Ser. No. 455,850

Term of patent 14 years

Int. Cl. D16—05

U.S. Cl. D16—30

FIG. 1

FIG. 2

FIG. 3

FIG. 4

FIG. 5

FIG. 6

FIG. 1 is a front perspective view of a coin operated reproduction machine showing our new design;

FIG. 2 is a front elevational view thereof;

FIG. 3 is a rear elevational view thereof;

FIG. 4 is a left side elevational view thereof;

FIG. 5 is a right side elevational view of said first embodiment; and

FIG. 6 is a top plan view of our design.

We claim:

The ornamental design for a coin operated reproduction machine, as shown and described.
